UNITED STATES PATENT OFFICE.

OTTO A. HEPPE, OF LA GRANGE, ILLINOIS.

DESIGN FOR A SHINGLE-SIMULATING STRIP.

57,126.

Specification for Design.

Patented Feb. 22, 1921.

Application filed September 4, 1917. Serial No. 189,699. Term of patent 14 years.

To all whom it may concern:

Be it known that I, OTTO A. HEPPE, a citizen of the United States, residing at La Grange, in the county of Cook and State of Illinois, have invented a new, original, and ornamental Design for a Shingle-Simulating Strip, of which the following is a specification, reference being had to the accompanying drawing, forming part thereof.

The figure is a plan view of a shingle simulating strip, showing my new design.

I claim:

The ornamental design for a shingle simulating strip as shown.

OTTO A. HEPPE.
